UNITED STATES PATENT OFFICE.

RICHARD THORN BECKETT, OF WOODBURY, NEW JERSEY.

BOTTLE-FORMING MACHINE.

SPECIFICATION forming part of Letters Patent No. 529,693, dated November 27, 1894.

Application filed December 22, 1892. Serial No. 456,008. (No model.) Patented in Belgium February 15, 1893, No. 103,197; in England March 11, 1893, No. 1,687; and in France April 26, 1893, No. 227,525.

To all whom it may concern:

Be it known that I, RICHARD THORN BECKETT, of Woodbury, Gloucester county, State of New Jersey, have invented a new and useful Improvement in Bottle-Forming Machines, (for which I have obtained a patent in Great Britain, No. 1,687, bearing date March 11, 1893; in France, No. 227,525, bearing date April 26, 1893, and in Belgium, No. 103,197, bearing date February 15, 1893,) of which the following is a specification.

I will describe a bottle-forming machine, embodying my invention and then point out the novel features in claims.

15 In the accompanying drawings, Figure 1 is a front view of a bottle-forming machine embodying my invention. Fig. 2 is a side view thereof. Fig. 3 is a front view showing certain parts in a different position from that 20 shown in Fig. 1. Fig. 4 is a side view thereof. Fig. 5 is an enlarged sectional detail showing a modification. Fig. 6 is an enlarged plan view of a certain part. Fig. 7 is an enlarged sectional detail of a certain part. Fig. 8 is a 25 plan and elevation of formers employed.

Referring by letter to the drawings A designates a standard extending from a suitable base A'.

A² shows a swinging standard pivotally connected at its lower end to bearings a extended upward from the base A'. The swinging standard A² carries the two part mold A³. Each part of the mold A³ at its lower end has a hinge or pivotal connection with a stud a' 30 on a plate or platform a², here shown as adjustably connected, by means of screws a³, to a plate a⁴ on the upper end of the swinging standard A². By means of the screws a³, the plate a² and the mold A³ may be adjusted 35 vertically. Each part of the mold A³ is connected by an adjustable link a⁵ with a lever A⁴, shown as pivoted at one end to an arm a⁶ on the plate or platform a². The levers A⁴, at the opposite end, are pivotally connected 40 by means of a bar a⁷, to the upwardly extending arms a⁸ of a brace bar A⁵. The brace bar A⁵ at its lower end extends through a slot opening in a plate a⁹ extended from the base A', and the bar is notched at its lower end to 45 form shoulders a¹⁰ adapted to rest on the upper surface of the plate a⁹, to hold the mold

in operative position, as shown in Figs. 3 and 4.

To prevent the standard A² from swinging too far forward a stop bolt A⁶ is employed. 55 This bolt has a pivotal connection with the standard A² and is extended through a sleeve a¹¹ which is movable through a hole in the front wall of the standard A. The sleeve a¹¹ has at each end an annular flange larger than 60 the opening through the standard and a spring a¹² interposed between the end of the sleeve a¹¹ and a nut a¹³ on the stop bolt A⁶, serves as a cushion to prevent jar when the standard A² is moved to its forward position. 65

A⁷ is a vertically movable rod provided with a plate or platform a¹⁴ at its upper end and having bearings in arms a¹⁵ projecting rearward from the standard A². These bearings are so arranged relatively to the standard A², that the rod A⁷ will assume a vertical position when the standard A² is in its forward position as shown in Fig. 2. The lower end of the rod A⁷ is connected by a link a¹⁶ to a fulcrumed treadle A⁸, which at its forward portion has a spring a¹⁷ extended from it to the standard A², which serves to return the rod A⁷ to its downward position. 70 75

B is the former for the bottom of a bottle adapted to engage in and form the bottom of 80 the mold A³ and to have a slight vertical movement imparted to it by the mold sections as they come together. The bottom former B has on its lower side a stem b movable in a socket formed in a lug b' on the plate or platform a². A bevel or cam surface b² is formed on the lower side of the bottom former adapted to engage with corresponding bevels or cam surfaces b³ in the lower portions of the mold sections. Obviously, when the mold sections 90 are forced together the bevel or cam surfaces b², b³, will force the bottom former upward and depress the bottom of the bulb of glass in the mold. 85

I will now describe the means for carrying 95 a bulb of glass to the mold and expanding or blowing the same.

B' designates a carrier here shown in the form of a wheel mounted on a tubular hub B², having a horizontal bearing B³ in the upper portion of the standard A. A pipe B⁴, provided with a valve b⁴, connects with the tubu-

lar hub B² and serves to convey air, under pressure, to the interior of the hub for the purpose of blowing a bottle as will herein-after appear.

5 C designates a tubular casing, the interior of which forms an air chamber having communication with the tubular hub B². The casing C is arranged at right angles to the hub B². It has at one end a cap or stuffing box C', and at the other end a cap or stuffing box C², which, as here shown, has an annular groove c formed in it.

C³ is a blow tube having bearings in the caps or stuffing boxes C' C² and movable longitudinally of the casing C. The blow tube has a stem portion c' extended through the stuffing box C' and provided with a head c² at its end. A spring c³ surrounds the stem between the head c² and the cap or stuffing box C' and serves to move the blow tube longitudinally to bring its end c⁴ wholly within the cap or stuffing box C². The blow tube is intended to be forced into the glass forming the neck of a bottle X and it is movable 20 through a sleeve F the projecting end of which is tapered to provide a former for the outwardly flaring mouth of the bottle. The chamber in the casing C communicates with the interior of the tube C³ through perforations c⁵, below a stop collar or sleeve c⁶ surrounding the tube C³ at one side of an annular shoulder c⁷ formed in the interior of the casing C. This shoulder and stop collar or sleeve prevents the spring c³ from moving the tube too far outward.

35 D designates tongs or formers for the exterior of the mouth of a bottle. The tongs or formers D are carried by the carrier B' on arms D'. The arms D' have interior heads 40 d to fit in the annular groove c of the cap or stuffing box C². The former sections D have a horizontal movement toward and from each other. An arm D' extends rearward from each tong or former section D and the arms 45 at the rear ends are pivoted on a bolt or stud d' on a bracket D² secured to the carrier B'. Each section of the former D is removably secured to its arm D' by means of a suitable thumb screw. The former sections are forced 50 together by means of springs d² bearing at one end against the arms D' and at the other end against lugs projecting from the bracket D². When desired, I employ a cam d³ engaging the inner sides of forwardly projecting 55 portions d⁴ of the arms D'. The cam consists of a plate mounted on a shaft d⁵, having a bearing in a plate d⁶ secured to the cap piece C². A handle d⁷ is provided for turning the cam plate. The former sections D hold the 60 glass in position, before the mold A³ is placed around it, by means of inwardly projecting beads or shoulders d⁸ which forms the lower portion of the head of the bottle.

E shows a holder or receiver for glass. It 65 is made in two separable sections adapted to fit closely together, similar to a mold A³. Each section is secured to an arm e. The

arms e are crossed and fulcrumed at their point of crossing to a stud e' extended from the carrier B'. Links e² are pivoted at one 70 end to the ends of the crossed arms e at e', and at the opposite end these links e² have a coincident pivotal connection with an operating lever E'. The lever E' has a pivotal connection e⁴ with the carrier B', and a yielding friction plate e⁵ is affixed to the carrier B' to engage with the lever E' and hold it as adjusted. Obviously, by moving the lever E' from one end to the other of the plate e⁵ the 75 links and arms may be operated to close or 80 separate the parts of the holder E as desired. It will be observed that the arms, links and lever first described are in the rear of the casing C, and that the ends of the arms e, connecting with the sections of the holder E are 85 extended forward so as to bring the holder sections in line with the casing C. When the sections of the holder E are closed together they engage around a portion e⁶ of the tongs or formers D. The carrier B' is intended to 90 be oscillated back and forth, a one half revolution, and I therefore provide stops. These 95 stops consist of a lug e⁷ extended rearward from the carrier, and lugs e⁸ extended from the standard A. When the lug e⁷ contacts 100 with one of the lugs e⁸, a further movement is prevented. Set screws e⁹ may be provided on the lugs e⁸, for the purpose of adjustment.

In Fig. 5, I have shown a sleeve F, surrounding the blow tube and within which the tube 105 is movable longitudinally. This sleeve has at its end a former for forming the mouth of a bottle. The sleeve has opposite slots f in its wall and a pin f' extended through the blow tube projects into those slots. An annular 110 shoulder f² on the blow tube normally at some distance from the end of the sleeve allows the end of the blow tube to be forced some distance into the mass of glass before the shoulder f² comes in contact with the end of the 115 sleeve to force the end of the sleeve into the mouth portion of the bottle. When the blow tube is allowed to resume its normal position the pin f' engaging with the end walls of the 120 slots will draw the mouth former out of the glass, into which a small amount of air is admitted before the parts are reversed.

In operation the machine is placed in the position shown in Figs. 1 and 2, with the formers D closed and the receiver E also closed. 120 After placing the glass in the receiver E, the blow tube is forced upward, by means of the treadle A⁸, the rod A⁷ and the link a¹⁶, to push the mouth former into the mass of glass. Then the rod A⁷ is allowed to lower, and a 125 small amount of air is admitted. Then the carrier is given a one-half rotation in the direction indicated by the arrow in Fig. 1, which will bring the parts thereon to a reverse position. Now the lever E' is operated to separate the receiver sections as shown in Fig. 3. By drawing upward on the bar a⁷ standard A² is caused to assume a vertical position and this motion causes the mold sections A³ to 130

close around the glass. The several parts of the machine will now be in the position shown in Figs. 3 and 4. While the parts are in this position the valve b^4 is opened to allow a pressure of air to enter and expand or blow the glass in the mold and form the bottle. After forming the bottle the mold A^8 is removed and also the formers D and then the bottle is removed.

10 Having described my invention, what I claim is—

1. In a bottle forming machine the combination with mold sections of the bottom former movable upward by direct engagement with said mold sections, substantially as specified.

15 2. In a bottle forming machine the combination with mold sections having inclined or cam surfaces, of a bottom former having the inclined or cam surface coacting with the inclined or cam surfaces of the mold sections to raise the bottom former, substantially as specified.

20 3. In a bottle forming machine, the combination with a carrier, a casing forming an air chamber and means for admitting air thereto, of the blow tube having the interior mouth former at its end, the pivoted tongs supporting formers for the exterior of the mouth, and a cam plate between the outer ends of said 25 tongs for separating them, substantially as specified.

30 4. In a bottle forming machine the combination with a carrier and a casing forming an air chamber, of the blow tube movable longitudinally in said casing a movable sleeve 35 in which said tube is movable and having a mouth former at its end, and means for moving said tube and also the sleeve, the tube in advance of the sleeve, substantially as specified.

40 5. In a bottle forming machine the exterior mouth former consisting of sections, pivoted arms to which said sections are secured and a cam plate for separating said sections located between the ends of the arms opposite their pivot, substantially as specified.

45 6. In a bottle forming machine the combination with a fixed standard, of a movable standard, a mold thereon consisting of separable sections and having a bottom former and means for moving the movable standard and automatically separating the mold and bottom former from a formed bottle, substantially as specified.

55 7. In a bottle-forming machine, the combination with means for blowing and supporting

a bottle, of a mold consisting of separable sections, a movable bottom former, a movable standard carrying said mold and former, and a brace for securing the standard, mold and formers in operative position by engaging a recess in the floor at its free end, substantially as described.

8. In a bottle forming machine the combination with means for blowing and supporting a bottle, of a mold consisting of separable sections, a movable bottom former unattached to the said mold sections, a movable standard carrying said mold and former and a brace for securing the standard, mold and former in operative position, substantially as specified.

15 9. In a bottle forming machine, the combination with separable mold sections, of a movable standard carrying said mold sections, levers pivoted to said standard, connections between said levers and the mold sections and a brace bar for securing said standard in operative position and holding said levers in their upward position, substantially as specified.

20 10. In a bottle forming machine, the combination with a carrier, of arms pivotally connected thereto an exterior mouth former, consisting of sections removably secured to said arms, springs for closing and a cam lever for opening said former by engagement with said arms, substantially as specified.

25 11. In a bottle forming machine, the combination of a movable standard, a plate attached to said standard having an adjustable connection therewith and a mold made in sections supported by said plate, substantially as specified.

30 12. In a bottle forming machine, the combination of a carrier, a casing forming an air chamber, arms pivoted to said carrier and engaging with said casing and an exterior mouth former secured to said arms substantially as specified.

35 13. In a bottle forming machine, the combination of a carrier, arms pivoted to said carrier, a receiver for glass secured to said arms and a lever pivoted to said carrier for moving said arms, substantially as specified.

40 In testimony whereof I have signed my name to this specification in the presence of two subscribing witnesses.

RICHARD THORN BECKETT.
